SAND BLAST NOZZLE CONTROL

William A. Rich, Leipsic, Ohio

Application May 27, 1947, Serial No. 750,660

3 Claims. (Cl. 51—11)

1

This invention relates to an improvement in sand blast nozzle controls.

In carving and lettering granite and marble, the usual practice is to direct a stream of sand blast abrasive normally against the face of the work. Such a device is commonly known as a straight shooter. A serious difficulty with machines of this type is that the spent abrasive collides with the oncoming abrasive, thereby greatly decreasing the efficiency.

It is a principal object of the present invention to provide a nozzle that will direct the abrasive against the sides of the letters or carvings. The nozzle is caused to oscillate, thereby permitting the exhaust to be cleared out of the way of the oncoming abrasive.

A preferred embodiment of the invention is shown in the accompanying drawings, but it is understood that modifications may be made without departing from the spirit of the invention as hereinafter claimed.

Figure 1 is a bottom plan view of the new and improved nozzle control.

Figure 2 is a side view of the structure shown in Figure 1.

Figure 3 is a side view of a modified form of nozzle control.

A hose 10 carries compressed air and abrasive and has attached thereto a nozzle 11. A concentric swivel 13 is attached either to the nozzle 11 or to the portion of the hose 10 adjacent the nozzle 11. A clamp 14 is gripped to the hose 10 rearwardly of the swivel 13, and an integral hinge 16 extends forwardly from the clamp 14, as best shown in Figure 2 of the drawings. Two resilient arms 18 are pivoted to the swivel 13 and are joined by a cross-piece 19 that is caught between the hinge 16 and the hose 10.

The hose 10 is shown slightly bowed upwardly in Figure 2. When the bowed portion of the hose 10 is depressed, the nozzle 11 will oscillate in a vertical plane to accomplish the desired carving. The amplitude of the oscillations of the nozzle 11 will be determined by the amount of bowing of the hose 10, and the latter is controlled by the spacing between the fixed swivel 13 and the clamp 14 that is made movable with respect to the swivel 13. As hereinbefore mentioned, the abrasive is directed against the sides of the letters or carving, and the result is a sharp, clear-cut incision. The movement of the nozzle 11 on the swivel 13 will greatly reduce the collision of the exhaust and the oncoming abrasive.

Of course, when it is desired to oscillate the nozzle 11 about a vertical axis, the entire device is shifted 90° about the axis of the nozzle. As

shown in Figures 1 and 2, the nozzle 11 is shown ready for use in a vertically oscillable movement.

In Figure 3 is shown a modified form of device. A collar 20 is positioned about the hose 10 between the swivel 13 and the clamp 14, and a lever 21 is pivoted to the collar 20 by any well known means, such as a ball-and-socket joint 23. The lever 21 is connected by a forward extension 25 to the swivel 13. The lever 21 will provide an easy means for depressing the hose 20 to produce the desired oscillation. A handle 27 may be positioned on one or both arms 18 to assist in manipulating the device.

I claim:

15. In combination with a hose and a nozzle, means for controlling the movement of the nozzle, comprising a swivel fixed to the hose adjacent the nozzle, a clamp fixed to the hose rearwardly of the swivel, and means for resiliently joining the swivel and the clamp, whereby the hose may be flexed between the swivel and the clamp.
20. In combination with a hose and a nozzle, means for controlling the movement of the nozzle, comprising a swivel fixed to the hose adjacent the nozzle, a clamp movably secured to the hose rearwardly of the swivel, and a spring arm pivoted to the swivel and resiliently and removably joined to the clamp, whereby the hose may be oscillated transversely between the swivel and the clamp.
25. In combination with a hose and a nozzle, means for controlling the movement of the nozzle, comprising a swivel fixed to the hose adjacent the nozzle, a clamp movably secured to the hose rearwardly of the swivel, a hinge extending from the clamp toward the swivel, a resilient U-shaped arm having its legs pivoted to the swivel and the base of the U frictionally held by the hinge, a collar mounted on the hose between the swivel and the clamp, and a lever pivoted to the swivel opposite the U-shaped arm and bearing against the collar, whereby pressure on the lever will flex the hose between the swivel and the clamp against the pressure of the U-shaped arm.
30. In combination with a hose and a nozzle, means for controlling the movement of the nozzle, comprising a swivel fixed to the hose adjacent the nozzle, a clamp movably secured to the hose rearwardly of the swivel, a hinge extending from the clamp toward the swivel, a resilient U-shaped arm having its legs pivoted to the swivel and the base of the U frictionally held by the hinge, a collar mounted on the hose between the swivel and the clamp, and a lever pivoted to the swivel opposite the U-shaped arm and bearing against the collar, whereby pressure on the lever will flex the hose between the swivel and the clamp against the pressure of the U-shaped arm.
35. In combination with a hose and a nozzle, means for controlling the movement of the nozzle, comprising a swivel fixed to the hose adjacent the nozzle, a clamp movably secured to the hose rearwardly of the swivel, a hinge extending from the clamp toward the swivel, a resilient U-shaped arm having its legs pivoted to the swivel and the base of the U frictionally held by the hinge, a collar mounted on the hose between the swivel and the clamp, and a lever pivoted to the swivel opposite the U-shaped arm and bearing against the collar, whereby pressure on the lever will flex the hose between the swivel and the clamp against the pressure of the U-shaped arm.
40. In combination with a hose and a nozzle, means for controlling the movement of the nozzle, comprising a swivel fixed to the hose adjacent the nozzle, a clamp movably secured to the hose rearwardly of the swivel, a hinge extending from the clamp toward the swivel, a resilient U-shaped arm having its legs pivoted to the swivel and the base of the U frictionally held by the hinge, a collar mounted on the hose between the swivel and the clamp, and a lever pivoted to the swivel opposite the U-shaped arm and bearing against the collar, whereby pressure on the lever will flex the hose between the swivel and the clamp against the pressure of the U-shaped arm.
45. In combination with a hose and a nozzle, means for controlling the movement of the nozzle, comprising a swivel fixed to the hose adjacent the nozzle, a clamp movably secured to the hose rearwardly of the swivel, a hinge extending from the clamp toward the swivel, a resilient U-shaped arm having its legs pivoted to the swivel and the base of the U frictionally held by the hinge, a collar mounted on the hose between the swivel and the clamp, and a lever pivoted to the swivel opposite the U-shaped arm and bearing against the collar, whereby pressure on the lever will flex the hose between the swivel and the clamp against the pressure of the U-shaped arm.
